UNITED STATES PATENT OFFICE.

ALEXANDER LYLE AND CHARLES OWENS, OF CHATTANOOGA, TENNESSEE; SAID, LYLE
ASSIGNOR TO DWIGHT P. MONTAGUE, OF CHATTANOOGA, TENNESSEE.

MACHINE FOR PRODUCING PRINTING-SURFACES.

No. 882,704.

Specification of Letters Patent. Patented March 24, 1908.

Application filed February 20, 1907. Serial No. 358,376.

To all whom it may concern:

Be it known that we, ALEXANDER LYLE and CHARLES OWENS, citizens of the United States, residing at Chattanooga, Tennessee, have invented certain new and useful Improvements in Machines for Producing Printing-Surfaces, of which the following is a specification.

Our invention relates to machines for forming raised printing surfaces on metal and the like for use in addressing machines for applying addresses to magazines, newspapers and other articles to be sent through the mails.

In carrying out our invention we employ key operated mechanism associated with die carrying wheels which wheels are driven by suitable power connections and which are adapted to receive between them the blanks to have the impressions made thereon, the said die wheels being so controlled through connections leading to the keys that they are arrested in different positions corresponding to the keys operated, and when so arrested the driving power is transferred from the rotating mechanism to means whereby the die wheels are brought together for making the raised characters on the blanks, both the rotary movement and the transferring of the power resulting from the operation of the appropriate keys. We have also provided a carriage for holding the blanks and automatic escapement for the said carriage, whereby a step by step feed is imparted thereto after the manner of an ordinary typewriter, the feed action, however, taking place after the dies have made their impression upon the blank therebetween. We have also provided certain means of control by the operator whereby he may position the carriage from the key-board for line spacing.

The invention consists in the features, combination, and arrangement of parts hereinafter described and particularly pointed out in the claims.

In the accompanying drawings,—Figure 1 is a front view of a machine embodying our invention. Fig. 2 is a vertical longitudinal section along the shafts of the die wheels and showing also the bank of finger keys and the connections leading therefrom for controlling the operation of the die wheels and associated parts. Fig. 3 is a plan view of a section taken substantially on line 3—3 of Fig. 1, the plane of this section being just

above the surface of the feed table for the blanks and in the plane of the space between the die wheels. Fig. 4 is a vertical transverse sectional view substantially on the line 4—4 of Fig. 2. Fig. 5 is a detailed sectional view substantially on the line 5—5 of Fig. 2, looking towards the left. Fig. 5^a is a view of one of the stencil blanks. Fig. 6 is a detailed view of the hopper for the blanks upon which the raised printing surfaces are to be formed together with one of the feed wheels or disks, and a part of the feed slide or table which co-operates therewith. Fig. 7 is a plan view of part of the feed mechanism. Fig. 8 is a side view of a part of the feeding mechanism partly in section. Fig. 9 is a detail of the carriage feed. Figs. 10 and 11 are detail views.

In these drawings, 1—2 indicate the die wheels between which the blanks of sheet metal or other material are fed to have the raised printing surfaces formed thereon said die wheels carrying coacting male and female dies. These die wheels each comprise two members between which the dies are clamped, one of these members 1^x—2^x is formed with a hub keyed or otherwise fastened to its shaft, marked respectively, 5—6, and the other member consists of a ring or plate 1'—2' held in place by bolts 7 and drawn against the dies which lie between these two members. A hardened steel ring 8 lies between the two members of the die wheel and these rings are designed to sustain the thrust and wear incident to the action of the dies which have their inner ends resting against the periphery of these rings. The holding of the dies between the two members is completed and rendered more effective by the screws 9 located near the periphery of the die wheels and extending from one member into the other. The die wheels are driven in unison through the gears 10—11 and power is communicated to the hollow shaft 5 of the upper die wheel through the clutch 12 to be hereinafter described from a shaft 13 extending through the hollow shaft 5 and having thereon the driving toothed wheel or sprocket 14 which is driven from any suitable source of power, as for instance, the shaft 15 having thereon the toothed wheel 16 which may be connected with the wheel 14 through a suitable chain 17.

The die wheels are normally in motion derived through the connections just referred

to, and we have provided means whereby upon the depression of a finger key representing the desired letter, the rotary motion of the die wheels is arrested so that these die 5 wheels are brought into position with the dies corresponding to the letter represented by the key depressed in proper alinement or in registered position and ready to perform the die action or that of making the raised 10 letter or character on the metal blank which now lies between them.

The arresting of the die wheels in proper registered position is performed through the operation of a finger key, a bank of such 15 keys being represented at 18, the levers of which are connected through rods 19 with levers 20 one for each key pivoted at 21 to brackets or ears 22 carried in a ring or frame 23 which in turn is supported on the frame 20 work 24 of the machine. From the levers 20, rods 25 one for each key extend to stop pins 26, slidably mounted in a frame or ring 27, which is supported in the main frame of the machine in fixed relation by, for instance, 25 the screws 28. The connection between the rods 25 and the stop or controlling pins 26 is a pivotal one at point 29, this pivot extending through a sleeve 30 which is held to the outer cylindrical portion 31 of the stop or 30 controlling pin 26 by a set screw 32. The stop or controlling pins are square or rectangular in cross section and are guided through the frame ring 27 before described. Springs 33 are arranged to retract the operating 35 connections just described on the release of the keys. The stop or controlling pins 26 are arranged in a circle adjacent the periphery of a disk or wheel 34 fixed to or formed with the hollow shaft 5 of the upper 40 die wheel, as shown in Fig. 2. This disk or wheel has pivoted thereto a bell crank lever 35, one end of which lies opposite the circle in which the stop or controlling pins lie, and the other arm of said lever enters an opening 45 36 in a sliding wedge block 37, which is guided to move radially of the wheel or disk 34 within a bracket or boxing 38. This wedge block carries a projection 39 extending through a slot 40 in the wheel or disk 34 50 and when the wedge block is moved radially inward the projection 39 will engage with an arm 41, which carries a clutch piece or block 42 normally engaging the toothed clutch 12, before mentioned, the said clutch wheel having 55 ratchet like teeth as shown in Fig. 4. The arm 41 is guided at the end of the hub of the wheel 34 between said hub and a plate 43 screwed thereto. A spring 44 tends constantly to hold the clutch piece 42 in engagement 60 with the clutch wheel 12 on the driving shaft 13 and thus through this connection the upper die wheel is driven, and from the shaft of which through the gears 10—11 and shaft 6 the lower die wheel is driven in 65 unison therewith. The wedge block 37 is

operated inwardly to release the clutch just described by means of the lever 35 striking against any one of the stop or controlling pins 26, which may have been projected inwardly or towards the right in Fig. 2 upon 70 the depression of one of the keys at the keyboard. The relation of the parts when this is about to occur is indicated in Fig. 5, it being understood that the projected stop or controlling pin then lies directly in the path 75 of the end of the lever 35 which is being carried around by the rotation of the wheel 34 moving in unison with the die wheels.

It will be understood that the contact between the bell crank lever 35 and the projected stop or controlling pin is a yielding one for the reason that the wedge block is free to move inwardly and to move the arm 41 of the clutch piece or block against the tension of the spring 44 and thus when the 80 lever 35 strikes one of the projected controlling or stop pins, the parts will be relieved from shock or strain by reason of the yielding feature of the bell crank lever just described. The die wheels having now been disconnected from the driving means and being now in position with the appropriate dies in register or in alinement, the next action to be performed is the bringing together or closing of the die wheels upon the blank interposed between them. This closing or bringing together of the die wheels is also controlled through the operation of the stop or controlling pins and the wedge block above described. For this purpose we arrange a 85 90 95 100 105 110 115 120 125 130 135 140 145 150 155 160 165 170 175 180 185 190 195 200 205 210 215 220 225 230 235 240 245 250 255 260 265 270 275 280 285 290 295 eccentric shaft through the clutch 58 to be presently described. The eccentrics are arranged within openings in boxes 59. Upon these boxes a cross head frame 60 rests and this frame is slidably mounted in vertical extensions 61 of the standard 57 above mentioned. The cross head frame carries the bearings 62 for the shaft 6 of the lower die wheel. The eccentric shaft 56 is held to the standard portion 57 by a cap piece 63. It will be understood that one complete revolution of the eccentric shaft will raise the cross head frame 60 and depress the same so that for this one revolution the lower die wheel will be given an up and down movement so as to perform its die action and return to its lower and normal position.

Returning now to the construction and operation of the clutch mechanism for accomplishing this die action, and returning the lower die to normal position, it will be seen that the clutch comprises the toothed wheel 58 on the shaft extending through the hollow shaft of the eccentrics, the said toothed wheel coöperating with a clutch block 64 carried by the slide 65 mounted to move between a face plate 66 and the face of the box or enlargement 67 at the end of the eccentric carrying shaft. The clutch slide 65 carries a pin 68 which is normally held in its uppermost position to maintain the clutch released, as shown in Fig. 2 by a flange or rest 69 on a trip lever 70 pivoted at 71 to a frame member 72 attached to or formed with one of the guide ways 61 for the lower cross head frame. This trip lever is under tension of a spring 73 tending to move its lower end towards the left in Fig. 4, and it is provided with an arm 74 arranged to be borne upon by the lower end of the rod 54, above mentioned, so that upon the depression of this rod, which as above described, occurs substantially simultaneously with the cessation of the rotary movement of the die wheels, the trip lever 70 will be operated to swing the lower end thereof towards the right and withdraw its flange or supporting surface 69 from beneath the pin 68 so that the clutch slide 65 under the tension of its spring will be free to move downwardly and throw the clutch block carried thereby into connection with the toothed wheel 58 and thus connect the constantly rotating shaft 58' with the sleeve or shaft 56 carrying the eccentrics 55 with the result above mentioned that the lower die wheel will be moved upwardly to coöperate with the upper die wheel and form the raised printing surface or device upon the blank which has been moved into position between the die wheels.

The downward movement of the operating rod 54 also results in the release of the said rod from the arm 74 of the trip lever allowing the immediate return of the said trip lever to its effective or operative position as soon as

it has performed its function of throwing in the clutch for the closing of the dies. This release of the rod 54 from the trip lever is accomplished by a cam surface 75 formed in a bracket or plate 76 suitably supported upon the frame member 72, upon which cam surface rides a pin 73 carried by a portion of the rod 54 so that upon the downward movement of the rod 54 it will press down upon the rod 74 and simultaneously therewith its lower end will be gradually moved laterally from over the said arm 74 to release the same after the trip lever has released the pin 68 for the setting of the die elevating clutch. This will allow the trip lever to resume its former position under the action of its spring 73, it being arrested by its arm 74 coming against a suitable stop, as for instance at 77. It is now in position to release the clutch after the die elevating mechanism has performed one revolution and has returned the lower die to normal position. This release of the die elevating clutch is performed by a roller 78 on the clutch slide 65 engaging a fixed cam 79 on the frame of the machine. This cam by acting against the roller 78 will raise the slide 65 against the tension of its spring and thus bring the pin 68 into range of the flange or rest 69 on the trip lever, and this being slightly inclined will complete the lifting of the clutch slide and the release of the die elevating clutch, and as above indicated, when this action takes place the lower die has been returned to its normal lower position and the parts are ready for another action.

During the operations above described, it will be understood that the key which has been depressed has been maintained in depressed position with its corresponding stop or controlling pin projected, and as a result of this the dies have been arrested in their rotary movement and have closed to make the impression after which the lower die has returned to its normal position. Now, upon the release of the depressed key the stop or controlling pin corresponding thereto is retracted within its guide ring 27 and the returning spring 49 now exerting its force moves the sleeve 45 towards the left, Fig. 2, thus pressing upwardly the wedge block by 115 acting upon the inclined surface thereof and this, freeing the clutch slide 41, allows its spring 44 to throw the clutch block or piece 42 into engagement with the clutch wheel, whereby the dies are again set in rotation and the machine is ready for the depression of another key, the only thing requiring to be done being the proper shifting of the blank to be operated on to bring another portion thereof between the dies or the replacing of the blank already operated upon by another blank.

One important feature of our arrangement and organization of parts is that the operations are carried on without shock and with-

out strain or wear on the parts due to the momentum of the machine, when for instance the dies are brought into alinement and are arrested, for it will be observed that the momentum of the machine under these conditions is absorbed by the closing action of the dies, or in other words, the power is transferred from the connections necessary to rotate the dies to the connections necessary to close them, and return them to normal position.

Should it be desired to make a second die action with the die wheels remaining in the same relative position, it is simply necessary to depress a special key 80, the lever of which is pivoted at 81 and is connected through a link 82 to an arm 83 on a shaft 84 journaled in the frame, which shaft carries an arm 85 connected by a link 86 with the arm 74, so that the trip lever 70 may, by depressing the key 80, be held in its extreme right-hand position, Fig. 4, so that it will not engage with the pin 68 when this is lifted by the roller 78 and cam 79, but on the contrary will permit the immediate reengagement of the clutch block and clutch wheel 58 as soon as the roller 78 leaves the cam 79, and thus the dies will be brought together for a second action, the blank having been moved to a different position to receive the second impression alongside of the first.

We will now describe the means for feeding and supporting the blanks in proper position to receive the impressions. The blanks upon which the impressions are made for forming stencil plates consist of thin sheet metal pieces having their edges turned over as represented at 87. These stencil plates or blanks are placed one upon the other in a hopper composed of the sides 88 secured to the frame at 89 in any suitable manner. These sides have flanges 90 projecting integrally to form ways 91 down which the blanks feed by gravity with the turned over edges directed downwardly. The blanks are received upon feed wheels or disks 92, one at each end of the blank, said wheels having each a pocket or recess 93 for receiving the blanks and for moving them downwardly to a reciprocating feed slide composed of the bars 94 and adapted to be moved in the ways 95 supported as will be hereinafter described.

In the rotation of the feed wheels the lowermost blank is moved from beneath the pile of blanks in the hopper and carried around by the said feed wheels between the same and the shield or flange 96 Fig. 6 formed on each of the sides of the hopper. The feed wheels are given a rotary reciprocating motion through the rack 114 and segmental gear 115 hereinafter mentioned, each movement being a half revolution, so that the blank carried by the feed wheels is moved from the hopper to a position below the feed wheels and in this action it is reversed in position so

that the turned over edges of the blank face upwardly. The blanks are delivered by the feed wheels upon feed arms 97 Figs. 6, 7 and 8 pivoted at 98 to the slide bars 94 and under tension of the springs 99, tending to press the feed arms upwardly. Each feed arm is provided with a finger 100 at its end adapted to grasp the edge of the blank to feed it into the machine and between the die wheels, this feed finger presenting an upwardly extending shoulder 101 to press against the edge of the blank. The spring arms 97 exert a controlling influence on the blanks while they are being moved by the feed wheels and while they are leaving the shield 96 and are assuming a horizontal position, and when this horizontal position is reached the blanks will leave the recess 93 on the feed wheels and rest upon the upper surface of the spring arms with its edge against the shoulder 101 of the finger 100 ready to be carried into the machine thereby. In order to hold the blanks on to the spring arms, we provide pins or grippers 102 carried by a spring arm 103 attached to the slide bar at 104. This spring arm has a cam shaped portion 105, which, when the feed slides retract or move outwardly to receive a new blank upon the feed arms 97, will ride against a projection 106, Fig. 4 which is on the lower part of the hopper and bears a fixed relation to the reciprocating parts of the feed mechanism. By the action of the cam 105 against this projection the gripper pins 102 are moved outwardly or are retracted so that the lower blank fed by the feed wheels 92 will be free to rest upon the feed arms 97, but as soon as the feed slides begin their inward movement to carry the blanks between the dies, the cam 105 by leaving the projection 106 will allow the spring arm 103 to exert its force and move the gripper pins over the upper surface of the blank resting on the feed arms, so that the said blank will be securely held by the combined action of the feed arms and gripper pins and will be accurately conveyed to the proper position between the dies.

The upward movement of the feed arms is limited by a pin 107 working in a recess or slot in the feed arms. The feed slides are connected together to move as one body by a table portion 108, and reciprocating motion is imparted to the feed slides by rack bars 109 secured thereto and meshing with an elongated gear 110 on a shaft 111 journaled in suitable bearings 112 in a supplemental frame 113. The feed slides and the feed wheels move in unison and are kept in proper time with each other by a rack bar 114 secured to rack bar 109 and meshing with a segmental gear 115 on the shaft 116 of the feed wheels, which shaft extends between the said feed wheels and is journaled in the sides of the hopper. Both of the feed wheels are secured to this shaft, they being connected 130

by a sleeve 117, which is pinned to the shaft. For rotating the gear 110 to give a reciprocating movement to the feed mechanism, the shaft 111 of the said gear is connected to a 5 gearing 118 with a shaft 119 extending in close proximity to the key board and having a crank or hand lever 120 by which the operator may rotate this driving mechanism just described and reciprocate the feed slides or 10 feed carriage.

In order to discharge the stencil which has been formed by the action of the dies on the blank, the feed carriage or slides are given a further movement inwardly to carry the 15 stencil from between the die wheels and to the point where the edge of the stencil is grasped by the discharge detents 121 pivoted in brackets 122 on the frame, the said detents having tail pieces 123 which limit their 20 downward movement and which maintain them by gravity in the position shown in Fig. 4 ready to grasp the edge of the stencil when moved thereunder. By these means the completed stencil will be discharged 25 from the machine. It will be understood that this action does not take place until after the necessary lines of impressions have been made in the blank and the stencil has been completely formed.

30 We have provided automatically operating mechanism for shifting the feed carriage or slide laterally so as to bring different parts of the blank between the dies for making a line of characters thereon. This automatic 35 action takes place after each die action, and of course at this time the feed carriage or slides are in their inward position, and the rack 114 is out of engagement with the segmental gear 115. The feed carriage is adapt- 40 ed to have the necessary lateral movement on the frame 113 for which purpose it is supported on the said frame by means of rollers 124 bearing on the rods 113' forming parts of the frame 113, the said rollers being sup- 45 ported in brackets 125 secured to the slides or parts of the feed carriage. The carriage is under tension of a spring in a barrel 126 suitably journaled on the frame and having a band 127 extending therefrom and con- 50 nected with a bar 128 secured at 129 to parts of the carriage frame. This bar is toothed, as at 130 Fig. 9 on its edge and constitutes the escapement bar of the carriage, its function being substantially similar to that of an 55 ordinary typewriter and coöperating with the escapement dogs 131—132, the former of which is pivoted at 133 to have swinging movement and carries the latter dog 132 slidably, this mechanism forming in itself 60 no part of my invention and being similar in all respects to an ordinary typewriter escapement mechanism. This escapement mechanism is operated automatically from the cross head frame 60, which raises and 65 lowers the lower die for which purpose we

provide a lever 134 having its end extending over a part of the cross head frame, as shown in Fig. 1, the said lever being pivoted to a bracket 135 and having its opposite end forked at 137 to embrace a rod 138 and rest 70 on an enlargement 139 of said rod so that as the cross head frame is raised the forked end of the lever will be depressed drawing down the escapement pawls so that the sliding member will be withdrawn from engagement 75 with the rack bar and will spring forward to get opposite the next tooth and upon the lowering of the cross head frame the escapement pawls will be raised to throw the swinging pawl out of engagement 80 and the sliding pawl into engagement, whereupon the carriage spring will draw the carriage to the left of Fig. 1 until arrested by the sliding pawl coming against the stop in the ordinary manner. The upward movement of the escapement pawls just described which occurs on the downward movement of the cross head frame is derived from a spring 139 connected at one end to a fixed arm 140 and to the tail piece 90 at its other end of the vertical swinging pawl 131. By this escapement mechanism after each die action the feed carriage is moved towards the left, Figs. 1, 2 and 3, so that the next die action will make an impression alongside of the previously made impression to form the characters of a word or the line of type or raised printing surface. We have also provided means for releasing the carriage from its escapement mechanism 95 100 by supporting the escapement pawls upon a pivoted piece 142 pivoted at the upper end of a standard 143 at the point 144. Further, by swinging the pawls as one body on this pivot 144 the carriage is free to move to the left under the action of its spring to the desired extent. In order to swing these pawls out of engagement, we provide a pin 145 projecting therefrom to be borne upon by an eccentric or slightly cranked portion 146 of a shaft 147 journaled in the bracket 148 and having ears 149 attached thereto and pivoted to parts of the carriage frame at 150 and by turning this shaft by a finger lever 151 this will bear upon the pin 145 and press the 110 115 same laterally together with the escapement pawl, thus completely releasing the carriage.

In order to operate the escapement mechanism from the key board to give a step by step laterally shifting movement to the carriage, we provide an arm 152 on a shaft 153 suitably journaled in parts of the frame, the said arm being connected with the lower end of the escapement operating rod 138 before described. The shaft 153 is connected to an 125 arm 154 and link 155 with an arm 156 on a rock shaft 157 suitably journaled in the frame and carrying another arm 158 connected by a link 159 with an arm 160 fixed to a lever or a frame 161 pivoted to the main 130

frame at 162. The space key 163 has a finger 164 reaching up over this space frame 161 so that each time the space key is depressed the connections described will be operated to give one step movement to the carriage towards the left, Fig. 1, to bring a new surface of the blank into position to be operated upon, this action taking place through the escapement mechanism above described. The space frame 161 and the space key and connections described are returned to normal position by a spring 165, connected to the frame at one end and to the arm 166 extending from a part of the space frame.

In order to give a step by step inward movement to the carriage for line spacing, we provide a key 167 at the key-board, the lever of which is pivoted at 168 and at its rear end is connected with a link 169, which is in turn connected with a pawl at 170 pivoted at 171 to a suitable part of the front frame with its end in position to engage the teeth of gearing 118 so that by depressing this key the train of mechanism leading to the gear 111 will be operated to move the carriage inwardly. It will be seen that the gear 111 is of elongated form so as to permit the lateral shifting of the carriage to take place for letter spacing.

From the above description it will be seen that we have provided a machine having certain characteristics of a typewriter in that the letter keys are operated corresponding to the address or the matter to be impressed upon the blanks and that with this mechanism we have combined certain power transmitting devices whereby when the impression is to be made the power is exerted entirely independent of any power exerted by the operator in manipulating the keys so that the impressions can be made upon metal or other material which will maintain permanently the raised printing surface or characters impressed therein.

It will be understood that the shaft 58' for raising the cross head frame and lifting the lower die to make the impression is driven constantly through the gears 58^a—58^b from the shaft 15, but as above set forth this shaft is normally disconnected from the eccentric shaft and the cross head frame, and together with the lower die wheel is in its lowest position normally. This cross head frame is of considerable weight and when the power is transferred from the connections which rotate the die wheels to the clutch which transmits the power to the cross head frame for the purpose of elevating it, the action takes place without shock, and the momentum of the machine is absorbed by this arrangement, as at the moment the die wheels are arrested, the momentum of the machine and the power are transferred to the cross head frame which must be lifted

thereby. Another important feature of our arrangement is the yielding quality of the bell crank stop lever 35, which, when it strikes one of the stop pins 26 yields to the extent necessary to force the wedge 37 downwardly against the sleeve 45 and retract the same against the tension of its spring. The wedge block must also overcome the tension of the spring 44 and by reason of this a cushioning effect is secured. A further important feature of our invention is that we drive the shaft 58' and the clutch ratchet 58 at a high rate of speed, namely, from two to four times as fast as the shaft 13 and ratchet wheel 12, this being due to the relative diameters of the driving and driven wheels 14 and 58^a and as the one clutch is thrown out of operation and the die wheels arrested in their rotation while the other clutch is thrown into operation to make the impression, the result is that said impression is made practically at the instant the dies are brought into proper position and arrested, so that even were there any tendency to rebound the closing of the die wheels takes place so quickly that the impression would be made before this rebound could occur.

Reverting to the timing of the feed wheels or disks 92 in relation to the feed slide, it will be understood that when the feed wheels have been turned so that the recesses 93 therein for receiving the blank have reached their upper position beneath the pile of blanks, the feed slide or carriage in contact with the blank is then in proper position to hold the blank between the dies to be operated on. The feeding of the blank from beneath the pile within the hopper conveying it to the feed slide or carriage and deposited thereon in engagement with the feed arms is automatically controlled by the carriage.

The feed arms 97 as above stated yield when receiving the blanks from the feed wheels, and they derive their yielding movement directly from the blank itself instead of being operated from independent mechanism.

It is of course important that each die when mounted in the die wheels is exactly the same height from the center of the said wheel as the other dies, and for this reason we make the die wheels of the three parts above described, and it will be noticed from Fig. 10 that the member 1^x is provided with radial ribs between which the dies are located. The thrust ring 8 fits within the recess at the inner end of these ribs and said thrust ring rests upon the hub of the die wheel, which hub is extended to afford a centering bearing for the ring or plate 1', which clamps the dies between itself and the plate or ring 1^x of the die wheel.

We claim as our invention:

1. In combination a rotary die carrier, a rotary impression member arranged with its

- impression surface in a plane parallel with the plane of the face of the die when in position to operate a sliding support, whereby the impression members are brought together, guide means at each end of said support whereby the parallel relation of the impression member and the die is maintained, means for driving the rotary die carrier and the impression means, stop means, keys and connections leading therefrom for operating the stop means and means whereby the power is transferred from the rotating mechanism to the die closing means, when the rotary movement is arrested by the stop, substantially as described. 10
2. In combination in apparatus of the class described, a rotary die wheel, an impression member adapted to be elevated in respect thereto, two constantly driven shafts, a clutch between one of said shafts and the die wheel, a clutch between the other shaft, and the means for elevating the impression member, stop means for arresting the die wheel, and means for simultaneously throwing one clutch out of connection and the other clutch into connection, said stop means and clutch controlling means being operated from the keys, substantially as described. 20
3. In combination in a machine of the class described, a die carrier and an impression member, means for rotating the die carrier, a clutch for controlling the said means, means for closing the die carrier and impression means together, a clutch for controlling the said closing means, key connections, stops arranged to be set thereby, and means to engage the said stops to arrest the movement of the die wheel and to positively operate both of the said clutches to control the 30 clutches, substantially as described.
4. In combination in a machine of the class described, a rotary die wheel, an impression member coöperating therewith, means for closing the die and impression member for the impression, a clutch controlling said means, a clutch controlling the rotary movement of the die, keys, stops arranged to be set thereby, and a coacting stop device rotating with the die wheel 40 and arranged to have movement on striking one of the stops, both of the said clutches being controlled from said coacting stop, by the movement thereof substantially as described. 50
5. In combination in a machine of the class described, a rotary die carrier, key connections, stops arranged to be set thereby, the stop member rotating with the die carrier, said stop member being adapted to yield, and a clutch controlled by the yielding movement of said stop member, and in turn controlling the rotary movement or stoppage of the die wheel, substantially as described. 60
6. In combination, the rotary die wheels, a clutch controlling the rotary movement of 65
- said die wheels, means for closing the die wheels, a clutch controlling the said closing movement, springs associated with said clutches, key connections, stops connected therewith, and a stop member rotating with 70 one of the die wheels and adapted to have yielding movement against the force of the said springs when said stop means strikes one of the key actuated stops, substantially as described. 75
7. In combination in a machine of the class described, a die carrier, an impression member, means for closing the impression member upon the die carrier, including a clutch with means for disconnecting the said clutch automatically when the impression member has returned to normal position, and connections whereby the said clutch may remain connected for a plurality of impression actions in succession, substantially as de- 80 scribed. 85
8. In combination in a machine of the class described, a die carrier, an impression member, a shaft and clutch for rotating the die carrier, means for elevating the impression member, a shaft and clutch for driving said elevating means, means for driving the said latter shaft at a higher rate of speed than the die carrier driving shaft, means for arresting the die carrier and means for throwing one clutch into operation and the other out, substantially as described. 90 95
9. In combination in a machine of the class described, a rotary die carrier, driving means therefor, including a clutch, key controlled stops, and a yielding stop member carried with the rotary die carrier to engage the said stops, substantially as described. 100
10. In combination in a machine of the class described, a rotary die carrier, an impression member, means for rotating the die, including a clutch, means for closing the impression member and the die carrier, including a clutch, a sliding sleeve connected to the latter clutch, stops, keys controlling the 105 same, a bell crank lever moving with the die carrier to engage the stops, a sliding wedge operated by the bell crank lever, said wedge being adapted to operate the clutch of the die carrier and to also operate the said sleeve, 110 115 substantially as described.
11. In combination in a machine of the character described, a die carrier, an impression member, means for closing the said die carrier and impression member, including a clutch, a trip lever for holding the clutch normally inactive, means for operating the said trip lever to release the clutch, said means then freeing the trip lever so that it may at once return to normal position, substan- 120 125 tially as described.
12. In combination in a machine of the character described, a die carrier, an impression member, means for closing the said die carrier and impression member, including a 130 135

clutch, a trip lever for holding the clutch normally inactive, means for operating the said trip lever to release the clutch, said means then freeing the trip lever so that it may at 5 once return to normal position, and means for releasing the clutch and placing it under the control of the trip lever, substantially as described.

13. In combination in a machine of the 10 character described, a die carrier, an impression member, means for closing the said die carrier and impression member, including a clutch, a trip lever for holding the clutch normally inactive, means for operating the said 15 trip lever to release the clutch, said means then freeing the trip lever so that it may at once return to normal position, and means for throwing the said trip lever out of normal position to permit a continuous action of the 20 clutch, substantially as described.

14. In combination in a machine of the character described, a rotary die wheel, a hollow shaft carrying the same, a second rotary die wheel or impression member, a rotary shaft carrying the same, gearing between the shafts of the said die wheels, a shaft 13, a clutch between the same and the hollow shaft of the die wheel, a vertically movable support for the second die wheel, 30 means for raising the said support to effect the impression, a clutch controlling said raising means, and key controlled means for operating the said clutches, substantially as described.

35 15. In combination, a hopper, carrier means for the blanks, comprising a yielding member, a reciprocating carrier therefor, and means for delivering the blanks upon the said yielding member, which under the pressure from the blank yields thereto, substantially as described.

16. In combination a hopper for the blanks, a recessed feed wheel, a sliding carrier means, a yielding feed arm on the sliding 45 carrier and means upon which the blank is delivered by the recessed feed wheel, substantially as described.

17. In combination in a machine of the

class described, die means, a movable frame carrying one of the die members, a carriage, means operated by the movement of said frame to give the carriage a step by step movement, and key operated connections for giving the carriage a step by step movement, substantially as described. 55

18. In combination, a hopper, a feed wheel having a recess to receive the blanks, a reciprocating carriage and a feed arm pivoted at one end and under spring tension to receive the blanks from the feed wheel, and to yield 60 in said action, substantially as described.

19. In combination in a machine of the class described, a reciprocating carriage, yielding feed arms thereon to grasp the blank, grippers to overly the blank, spring 65 supports carrying the said grippers, and means for moving the said spring supports and grippers to one side when the carriage is moved forward to receive a fresh blank, substantially as described. 70

20. In combination in a machine of the class described, a die carrier, an impression member, a frame carrying the said impression member, means for guiding the said frame vertically, an eccentric shaft, a drive 75 shaft within the same, a clutch between the said eccentric shaft and drive shaft, and means controlling the said clutch, substantially as described.

21. In combination in a machine of the 80 class described, a rotary die carrier, an impression member, driving means including clutch mechanism, key controlled stops and a yielding stop member to arrest the rotary movement of the die carrier and means 85 whereby the yielding action or movement of the stop member controls the clutch mechanism, substantially as described.

In testimony whereof, we affix our signatures in presence of two witnesses.
